UNITED STATES PATENT OFFICE.

CRAIG R. ARNOLD, OF PHILADELPHIA, PENNSYLVANIA.

DESIGN FOR AN ENGINE-FRAME.

SPECIFICATION forming part of Design No. 14,404, dated November 13, 1883.

Application filed May 15, 1883. Term of patent 14 years.

To all whom it may concern:

Be it known that I, CRAIG R. ARNOLD, a citizen of the United States, residing in the city of Philadelphia, in the State of Pennsylvania, have invented a new and original Design for Engine Frame and Cylinder, of which the following is a description and specification.

My design has reference to the frame and cylinder of an upright or vertical engine.

In the accompanying drawings, Figure 1 is a sectional side elevation, and Fig. 2 a sectional end view.

B is the base-plate, of ordinary shape, and

h h are two upright housings. S S are standards, each of which has an extension, as shown.

I claim as new and original—

The design for engine frame and cylinder, of the form and configuration substantially as shown and described.

In testimony whereof I have hereunto signed my name to this specification in the presence of witnesses.

CRAIG R. ARNOLD.
